HYDRAULIC TURBINE.

1,309,809.

Specification of Letters Patent. Patented July 15, 1919.

Application filed April 29, 1918. Serial No. 233,583.

To all whom it may concern:

Be it known that I, ARNOLD PFAU, a citizen of the United States, residing at Milwaukee, in the county of Milwaukee and State 5 of Wisconsin, have invented a certain new and useful Improvement in Hydraulic Turbines, of which the following is a specification.

This invention relates to improvements in 10 the construction of hydro-electric installations and is particularly applicable to hydraulic turbine installations of the direct connected, vertical shaft type.

An object of the invention is to provide a 15 hydraulic installation which is of simple and rigid construction, efficient in operation, and in which the cost of installation is reduced to a minimum.

The present invention is particularly applicable to hydro-electric installations of the type in which a turbine runner is direct connected to the lower extremity of a vertical main shaft, to the upper extremity of which a generator rotor is direct connected, and 25 in which a pit of sufficient vertical height is provided between the hydraulic and electric machines to permit ready access to the turbine controlling mechanism and to the main shaft bearing. In installations of this type 30 it is also desirable in many cases to locate the generator at a sufficient height above the turbine to place it beyond danger of flooding by the head waters, such location of the generator also being a factor affecting the 35 pit depth.

It has heretofore been customary in installations of the vertical shaft type wherein the generator is of such overall diameter that it extends considerably beyond the 40 periphery of the turbine speed ring, to utilize a cast metal spiral inlet casing and to support the generator and associated elements directly upon this casing. Such cast metal casings are, however, both expensive to construct and to transport when made of sufficient strength to withstand the high internal and external pressures to which they are subjected after installation.

In order to reduce the initial cost of construction and of transportation, as well as to increase the ability of the casings to withstand internal pressures, it has been proposed to form the inlet casings of sheet steel instead of cast iron or steel as heretofore. By

thus forming the inlet casings it has been 55 found that the weight thereof can be considerably reduced without sacrificing necessary strength to resist internal pressures, although these relatively light sheet metal casings are not capable of resisting external 60 pressures sufficiently to adapt them to bear the weight of the generator and associated parts.

It has heretofore been proposed in order 65 to relieve the sheet metal casings of excessive external pressures, to provide a series of struts or columns extending from the generator downwardly through the inlet casing to the foundation, in order to support the weight of the generator directly from the 70 foundation. Such proposed structure while accomplishing its object, is objectionable in that the columns provide undesirable obstructions in the inlet passage leading to the turbine and also because the columns penetrate 75 the sheet metal of the casing, thereby weakening the same. The struts or columns of this prior device must also be made of considerable strength and consequently of relatively large cross-section, due to their 80 segregation from each other and to the enormous weight which they must support.

The present invention contemplates elimination of the undesirable features of these prior structures but permits the use of the 85 highly desirable and efficient sheet metal casing, without undesirably increasing the cost of construction and of transportation. These results are accomplished by providing 90 a continuous metal ring which is connected directly with the turbine speed ring and has a flange extending laterally over the inlet casing, upon which the generator and the associated elements are supported. By making this supporting ring continuous and of 95 frusto-conical shape, the same may be made comparatively light in structure in order to provide the necessary strength. The supporting ring is, moreover, constructed of relatively short vertical height in order to 100 reduce to a minimum the weight thereof and hence the cost of transportation. In order to provide a pit of sufficient or necessary height between the turbine and the generator, an annular wall of concrete is provided 105 between the generator and the supporting ring. This concrete wall can be constructed at relatively low cost from ma-

terials obtainable at the place of installation.

A clear conception of an embodiment of the invention may be had by referring to the drawing accompanying and forming a part of this specification in which the various parts are referred to by suitable reference characters.

The single figure of the drawing represents a transverse vertical section through a direct-connected hydraulic turbine installation of the vertical shaft type.

The reaction turbine runner 1 is direct-connected to the lower extremity of a vertical main shaft 2 to the upper extremity of which the rotor of a dynamo-electric machine 3 is also direct-connected. The turbine runner 1 is housed within a suitable turbine casing 15 having a main shaft bearing associated therewith. The turbine casing 15 is supported upon the main foundation 12 and has a cast metal speed ring 5 associated therewith adjacent the periphery of the runner 1. The speed ring 5 is of usual construction having stationary guide vanes 6 and being also supported directly upon the foundation 12. Between the stationary guide vanes 6 of the speed ring and the inlet opening to the runner are located a series of adjustable guide vanes 4 which are manipulable by means of guide vane actuating mechanism of usual construction, not shown, associated with the upper extremities of the guide vane stems. The sheet metal spiral casing 7 forms a fluid conducting conduit 13 for conducting water from the penstock to the speed ring. The discharge end of the turbine runner 1 communicates with the tail race through the usual draft tube 8.

Between the dynamo-electric machine 3 and the hydraulic turbine is a turbine pit 9 access to which is effected through a passage 14. Surrounding the lower extremity of this pit is a rigid supporting ring 10 comprising a frusto-conical downwardly converging wall 18 and an outwardly projecting horizontal flange 16 having bracing ribs 19 and formed integral with the upper extremity of the wall 18. The ring 10 is comparatively light in structure but is of sufficient rigidity and strength to provide a stable support for a relatively great weight resting upon the flange 16. The lower extremity of the wall 18 rests directly upon and is secured to the top of the speed ring 5. The upper flange 16 extends laterally relatively to the direction of flow of fluid, over the relatively light yieldable casing 7 which is preferably formed of sheet metal or similar yieldable material. The casing 7 is of such form that it will readily resist enormous internal pressures but will not safely withstand excessive external loading such as the weight of a generator without

yielding and possibly collapsing. Surrounding the pit 9 and located directly above and in vertical alinement with the flange 16 of the ring 10, is a preferably annular concrete wall or pier 11 which spans the gap between the dynamo electric machine 3 and the supporting ring 10. The flange 16 of the ring 10 is preferably provided with a number of relatively small openings 20 for facilitating union of the concrete wall 11 with the concrete foundation 12. The structure is however such that substantially the entire weight of the wall 11 and of the superposed elements is carried by the ring 10 and speed ring 5.

It will be noted that the generator 3 is of such diameter that it projects a considerable distance over the body of the spiral casing 7. This is ordinarily the case in installations of this kind operating at relatively low speed. By providing the supporting ring 10 which is supported from the foundation 12 through the speed ring 5, forming this ring so as to extend outwardly over the casing 7 to points directly below the outer portion of the generator 3, and inserting the concrete vertical wall 11 between the generator 3 and the ring 10, a rigid support is provided between the generator 3 and the foundation 12 without in any manner interfering with sheet metal casing 7. The only external pressure which this casing 7 is required to withstand is the negligible pressure due to the weight of the concrete embedding the same, substantially the entire weight of the generator 3, and concrete wall 11 and the pit ring 10 being borne by the foundation 12 through the speed ring 5. By avoiding extension of the supporting ring 10 from the speed ring 5 to the lower surface of the generator and along the entire length of the pit 9, the weight of this ring may be reduced to a minimum thereby minimizing the cost of construction and of transportation thereof. By forming the ring 10 continuous and of outwardly flaring shape, the weight thereof may be reduced to a minimum thus further reducing the cost of construction and of transportation.

While the invention has been disclosed as applied specifically to a vertical shaft turbine of the Francis type, it will be noted that the same is applicable to other types of hydraulic machines. It should be understood that it is not desired to limit the invention to the exact details of construction herein shown and described for various modifications may occur to a person skilled in the art.

It is claimed and desired to secure by Letters Patent:

1. In a hydraulic machine, a fluid conducting casing, a foundation, means carried by said foundation and extending laterally over

said casing, a dynamo-electric machine above said casing, and an intermediate support between said machine and said means.

2. In a hydraulic machine, a fluid conducting casing, a speed ring associated with said casing, a foundation upon which said speed ring is supported, means carried by said speed ring and extending laterally over said casing, a dynamo-electric machine above said 10 casing, and an intermediate support between said machine and said means.

3. In a hydraulic machine, a sheet metal casing, a speed ring associated with said casing, a foundation supporting said ring, 15 a turbine runner adapted to receive fluid from said casing through said speed ring, a dynamo-electric machine connected to said runner and located above said casing, and a plurality of supports arranged in series between said machine and said ring.

4. In a hydraulic machine, a fluid conducting casing, a foundation, a speed ring supported by said foundation and associated with said casing, a continuous ring carried 25 by said speed ring and extending laterally over said casing, a dynamo-electric machine above said casing, and an intermediate support between said machine and said continuous ring.

5. In a hydraulic machine, a sheet metal casing, a foundation, a speed ring supported by said foundation and associated with said casing, a continuous metal ring supported by said speed ring and extending over said 35 casing, a dynamo-electric machine above said casing, and a concrete wall between said machine and said continuous ring.

6. In a hydraulic machine, a fluid conducting casing, a foundation, means carried by 40 said foundation and extending laterally over said casing, mechanism located above said casing, and an intermediate support between said mechanism and said means.

7. In a hydraulic machine, an annular 45 fluid conducting casing, a foundation, a speed ring associated with said casing and supported upon said foundation, means car-

ried by said speed ring and extending laterally over said casing, mechanism located above said casing, and an intermediate support between said mechanism and said means. 50

8. In a hydraulic machine, a yieldable fluid conducting casing, a foundation, rigid means carried by said foundation and extending laterally over said casing, mechanism above said casing, and an intermediate support between said mechanism and said rigid means. 55

9. In a hydraulic machine, a yieldable 60 fluid conducting casing, a foundation, a rigid speed ring associated with said casing and supported by said foundation, a rigid member carried by said speed ring and extending laterally over said casing, mechanism located above said casing, and a concrete wall between said mechanism and said member. 65

10. In a hydraulic machine, a fluid conducting casing, a foundation, means carried 70 by said foundation and affording a base of substantial width extending over said casing, mechanism located above said base, and an intermediate support between said mechanism and said base. 75

11. In a hydraulic machine, a yieldable fluid conducting casing, a foundation, rigid means carried by said foundation and affording a base of substantial width extending over said casing, mechanism above said 80 casing, and an intermediate support between said mechanism and said base.

12. In a hydraulic machine, a yieldable spiral fluid conducting casing, a foundation, a speed ring associated with said casing and 85 supported by said foundation, a rigid element associated with said ring and affording a base of substantial width extending over said casing, an energy absorbing device located above said base, and a concrete wall 90 between said device and said base.

In testimony whereof the signature of the inventor is affixed hereto.

ARNOLD PFAU.
